UNITED STATES PATENT OFFICE.

JOHN ROGERS FLANNERY, OF PITTSBURGH, PENNSYLVANIA, ASSIGNOR TO FLANNERY BOLT COMPANY, OF PITTSBURGH, PENNSYLVANIA.

STAYBOLT STRUCTURE.

1,364,098.

Specification of Letters Patent.

Patented Jan. 4, 1921.

Application filed September 10, 1919. Serial No. 322,866.

To all whom it may concern:

Be it known that I, JOHN ROGERS FLANNERY, a citizen of the United States, and a resident of Pittsburgh, in the county of Allegheny and State of Pennsylvania, have invented certain new and useful Improvements in Staybolt Structures; and I do hereby declare the following to be a full, clear, and exact description of the invention, such 10 as will enable others skilled in the art to which it appertains to make and use the same.

This invention relates to improvements in staybolt structures for boilers,—one object 15 of the invention being to provide a staybolt structure in which the bearing member and bolt may be assembled at the shop and said bearing member secured by welding to the outer face of the outer boiler sheet around 20 the bolt opening when the structure is installed in a boiler to connect the outer and inner sheets thereof, and constitute a closure for the bolt opening.

With this and other objects in view, the 25 invention consists in certain novel features of construction and combinations of parts as hereinafter set forth and pointed out in the claims.

In the accompanying drawings; Figure 1 30 is a sectional view showing an embodiment of my invention, and Fig. 2 is a view showing another embodiment of the invention.

1 represents an outer boiler sheet and 2 the inner sheet of a boiler. The outer boiler 35 sheet is provided with a bolt opening 3, the diameter of which is appreciably greater than that of the staybolt 4 which passes through it. The inner boiler sheet may be provided with a threaded opening for the accommodation of the threaded portion 5 of the staybolt.

The head 3^a of the staybolt (which may be partly spherical or rounded as in "flexible" staybolt structures) may be assembled 45 in the shop, in a bearing member 6 and said staybolt may be provided (for testing purposes) with a tell-tale hole 7 which may extend from the inner end of the bolt and terminate at its outer end within the head 3^a.

50 The bearing member 6 may consist of a hollow forging and may be made in either a single piece or a plurality of united forgings, and the contour of the interior of said bearing member is such as to provide a 55 rounded seat 8 for the rounded head of the

staybolt and a clearance space 9 to provide for longitudinal play of the bolt. The inner wall of the bearing member may be rounded at the inner end of the latter as indicated at 10, and the inner end of said bearing member is so formed as to provide a face 11 whereby the same may be seated against the outer face of the boiler sheet around the opening therein (forming a closure for said opening) and the inner curved 60 end portion 10 of said bearing member adjacent to the neck of the bolt may overlie a portion of the opening 3 in the boiler sheet.

The bearing member may be forged over the head of the bolt at the shop and the inner end of the bolt will be provided with a projecting angular portion 12 which may be grasped with a suitable tool whereby (when the devices are being installed) the inner end of the bolt may be screwed through 75 the opening in the inner boiler sheet.

When the staybolt shall have been passed through the inner boiler sheet, with the bearing member seated on the outer boiler sheet, the bearing member will be intimately united to said outer boiler sheet by a weld 13 and the angular projecting end 12 of the bolt will be removed and the inner end of the bolt will then be upset against the inner face of the inner boiler sheet, as indicated at 14.

It will be observed that the member 6 provides a bearing for the bolt head and also a closure for the opening in the boiler sheet.

The bearing member 6 may be made with 90 a hexagonal or other angularly shaped portion 15 to receive a suitable holding tool, and the inner end of the opening in the bearing member may be made flaring at 16.

Having fully described my invention what 95 I claim as new and desire to secure by Letters-Patent, is:—

1. In a staybolt structure, the combination with a boiler sheet having a bolt opening, and a staybolt having a head, of a 100 bearing member for said head located wholly outwardly beyond the outer face of the boiler sheet and secured to the latter, said bearing member permanently inclosing said head.

2. In a staybolt structure, the combination with a boiler sheet having a bolt opening, and a staybolt having a head, of a bearing member for said head seated on and 110 welded to the outer face of the boiler sheet

and permanently inclosing the head of the staybolt.

3. In a staybolt structure, the combination with a boiler sheet having an opening, of a hollow member seated on the outer face of the boiler sheet and covering said opening and having a part overlying a portion of said opening, said member also having a bearing therein for the rounded head of a staybolt, a staybolt having a head perma-

nently inclosed in said member, and weld uniting said member to the boiler sheet.

In testimony whereof, I have signed this specification in the presence of two subscribing witnesses.

JOHN ROGERS FLANNERY.
